UNITED STATES PATENT OFFICE.

FERNAND E. D'HUMY, OF ENGLEWOOD, NEW JERSEY.

AIRSHIP.

Application filed March 18, 1926. Serial No. 95,643.

An object of the present invention is to provide a strong, durable and fire-proof structure, for a dirigible airship.

Another object of the invention is to provide, for an airship of the dirigible type, a metal envelope adapted to yield under the stress of strong wind pressure and accommodate itself to distortions of the frame structure without danger of rupture, the envelope being adapted to regain its normal form when relieved of pressure.

Another object of the invention is the provision of an airship structure comprising a resilient frame and a resilient metal envelope enclosing it, both frame and envelope being adapted to yield and cushion the impact of a strong blast of wind and to restore the ship to its normal shape when relieved of a distorting stress, the metal envelope being so constructed as to adapt it to be either stretched or compressed longitudinally without danger of rupture or permanent distortion.

A further object is the provision of an envelope for an airship adapted to strongly reinforce the frame structure which it encloses.

In the drawings:

Fig. 1 is a side elevation of my improved airship;

Fig. 2 a sectional perspective view upon a larger scale showing the detail structure of the envelope;

Fig. 3 a longitudinal sectional view of a portion of the frame and envelope of the airship, with the gas bags removed;

Fig. 4 a longitudinal sectional view of the entire airship;

Fig. 5 a transverse section taken on the line 5—5 of Fig. 4;

Fig. 6 a transverse section taken on the line 6—6 of Fig. 4, and

Fig. 7 a sectional perspective view showing a modified form of frame structure.

The frame structure of the airship may be of any suitable construction. That shown in the drawings and described herein is of substantially the same form as that disclosed in my co-pending application Serial No. 69,833. This structure includes a longitudinal central beam or shaft S which extends throughout the length of the ship and constitutes a longitudinally extending compression member of a truss. The shaft S is

formed of a plurality of straight tubular sections 1 arranged end to end in axial alignment. Each tubular section is formed of thin metal and is filled with a light weight filler 2 such as a specially prepared wood pulp compounded to resist compression. The opposed ends of the different sections are connected together by flexible and resilient joint structures. These structures are not illustrated in detail in the present case but are diagrammatically indicated at 3 in Fig. 4. The joints are adapted to permit the shaft S to flex slightly under a transverse stress and tend to straighten it when the stress is removed.

Encircling the central shaft are a plurality of rings or hoops H. These hoops are disposed concentrically with the shaft and arranged therealong in equally spaced positions and in substantially the same transverse planes with the joints between the shaft sections. Each hoop is formed of a series of curved tubular sections 4. These sections are formed of thin metal and are completely filled with wood pulp, or other suitable material 5 to strengthen them. The opposed ends of the sections are joined together by suitable joint structures, indicated at 6. The hoops H are compression members and resist strains tending to force them inwardly toward the shaft.

A series of tension strands 7, formed of wire or cable, are connected in any suitable manner, to the shaft S at each joint thereof, as at 8, and extend radially outward from the joint and toward the hoop which encircles it. The strands of each series are equally spaced around the joint and their outer ends are connected to coiled springs 9. These springs are in turn anchored to the hoop in any suitable manner. A pair of opposed anchor rings 10 encircle each shaft joint and are disposed concentric with it. The radial strands 7 of each series are arranged in the same plane and the opposed rings 10 are disposed at opposite sides of the series of strands. The rings are held in place upon the strands by a series of bolts 11 which clamp the rings to opposite sides of the strands. Leading from each ring 10 to the next adjacent shaft joint 3 is a series of diagonal tension strands 12 formed of wire or cable. These strands lead from points equally spaced around the rings and are connected to

the next adjacent shaft joints at opposite sides of the rings. The diagonal strands leading from adjacent pairs of anchor rings therefore cross at points substantially midway the length of each shaft section 1. At their outer ends the strands 12 are connected to strong coiled tension springs 13 which are in turn connected to the rings 10. The rings 10 surrounding the joint between the front shaft sections are connected with the front end of the shaft by the strands and springs 12 and 13 respectively.

Surrounding the shaft S and spaced along it are a plurality of gas bags 14. Each bag is curved to describe the greater portion of a circle, a gap 15 being left between the closed ends of the bags. The gaps 15 are arranged in longitudinal alinement in order to provide a corridor space extending 20 throughout the length of the ship, below the shaft.

The frame structure and the gas bags are enclosed by an envelope E. This envelope comprises a series of annular sections formed of metal and connected together at their ends to form a continuous covering which extends over the entire length of the frame. The envelope sections are in four different forms designated respectively 16, 17, 18 and 19. The detail structure of these sections is shown in Figs. 2 and 3 of the drawings. Each section 16 surrounds one of the hoops H. The hoop is located midway between the ends of the section 16 and is formed with a straight annular face 20 which provides a seat for a straight medial portion 21 of the envelope section. The section 16 is securely held to the hoop by a ring 22 which encircles the straight portion 21 and is fastened to said portion and to the hoop in any suitable manner, as by bolts or rivets 23. The section extends outwardly from opposite sides of the hoop and is formed with circumferentially extending corrugations 24. Each edge of the section is folded inwardly upon itself around a circular wire 25 to form a bead-like edge. One of the folded edges is clamped between a pair of inner and outer rings 26 and 27 respectively. These clamping rings are formed to fit around the bead and are secured together at opposite sides thereof in any suitable manner, as by rivets or bolts 28.

The section 17 is much shorter than the section 16 and one of its end edges is formed to overlap the outer face of a marginal extension 29 formed upon the outer clamping ring 27. A ring 30 encircles the overlapping edge and the extension 29 and is securely fastened to them in any suitable manner as by rivets 31. The opposed ends of the sections 16 and 17 are thus connected together through the medium of the clamping rings 26 and 27. The opposite edge of the section 17 is turned inwardly for a material

distance to form an annular portion 32 spaced inwardly from the body of the section and concentric with it.

The envelope section 18 is a companion to the section 17 and is of very similar form: 70 The section 18 has one of its edges turned outwardly and backwardly in a reverse direction to the inwardly folded edge 32 of the section 17. The outwardly folded edge of the section 18 forms an annular portion 33 75 spaced from the body of the section and concentric with it. The section 18 is formed to fit within the section 17. The folded edges of the two sections define, in cross section, elongated hooks opening in opposite directions. These hooks are engaged so that the inturned edge of the section 17 lies within the hook of the section 18, and the out-turned edge of the section 18 is disposed within the hook of the section 17. This manner of connecting the sections adapts them for relative longitudinal sliding movement, and also provides a substantially weather-tight joint between them. The opposite edge of the section 18 is secured to the 80 outer one of a pair of clamping rings 34 and 35. These rings are similar to the clamping rings 26 and 27 and the marginal edge of the section is secured to the outer face of the ring 35 by means of a ring 36 85 and rivets or bolts 37.

The envelope section 19 is straight in longitudinal section and each of its edges is folded inwardly about a circular wire 38 to form a bead. One of the beaded edges is 100 clamped between the rings 34 and 35 in a manner similar to the clamping of the beaded edge of the section 16. The opposite edge of the section 19 has its bead clamped between a pair of inner and outer clamping rings 39 and 40 respectively. The opposed faces of these rings are formed with two spaced pairs of channels adapted to receive, respectively, the beaded edge of the section 19 and the adjacent beaded edge of the next succeeding section 16. Fastening elements 41, which may be bolts or rivets, hold the rings 39 and 40 firmly clamped about said beaded edges. The different forms of envelope sections are arranged in 115 this sequence between each pair of hoops H throughout the length of the airship. The sections at the ends of the ship are sharply conical in form and are connected to the ends of the central shaft S in any suitable manner.

The inner clamping rings 26 and 34, located at opposite sides of the sliding joint between the sections 17 and 18, are formed with inwardly extending flanges 26^a and 34^a, 125 respectively. These flanges extend around the inner side of the envelope and are connected together by a series of long tensioning bolts 42 spaced along the length of the flanges and provided with nuts 43. Each 130

hoop H is thus connected to the next adjacent hoops at its opposite sides by a tension structure comprising the envelope sections 16 and 19 and the bolts 42 connecting said sections.

The envelope sections are preferably made of a lightweight, strong, durable and resilient metal such as aluminum. They may, however, be formed of any suitable material. By forming the circumferential corrugations 24 in the sections 16 these sections are rendered resilient and are adapted to be either stretched or compressed in the longitudinal direction of the airship. Each section 16 is securely fastened to one of the hoops; and the next adjacent section 19, at one side of the hoop is securely connected to the tensioning bolts 42 and to the envelope section 16 secured to the next adjacent hoop. The tension of the envelope between the two hoops is adjusted by means of the nuts 43, the intermediate sections 17 and 18 sliding upon each other at their joint to accommodate themselves to different adjustments. A resilient tension exists in the envelope between the various hoops throughout the length of the ship.

The frame structure and the envelope together maintain the shape of the airship under normal conditions but are adapted to yield resiliently under the impact of a powerful wind force upon the outer envelope and prevent their permanent distortion or rupture. When the undue pressure is relieved the various frame parts and the various envelope sections resume their normal shapes and relative positions. The radial strands 7 and their connected springs extending between the shaft S'' and the hoop sections, together with the longitudinal tension exerted by the envelope structure, yieldably hold the hoops in their proper positions with relation to the shaft. The diagonal tension strands 12 and their connected springs yieldably hold the shaft sections in alignment. These diagonal strands 12 and their connected springs exert a pull both longitudinally and laterally outward at the shaft joints and are arranged to hold the shaft sections together end to end in series under compression throughout the length of the shaft, and are adapted also to yieldably resist buckling of the shaft. The resilient envelope structure is also adapted to yield under a strong buckling stress without danger of rupture, permanent distortion or separation of its sections. The ship structure is, therefore, adapted to cushion a blow received from any direction and to right itself when relieved of pressure.

The strong fireproof metal envelope structure provides the maximum protection for the enclosed frame structure and gas bags. In addition the envelope structure is especially designed to strongly reinforce the

frame structure. A great many frame parts may therefore be eliminated to simplify the structure and reduce its weight. The design of the envelope provides the very desirable feature of resilience without a sacrifice of strength or durability. It will be obvious that the envelope is susceptible of variations in its structure, and also that it may be used in connection with frame structures other than that shown. I do not wish to be limited, therefore, to the specific structures disclosed.

The hoop sections 4 are shown in Figs. 2 and 3 as square in cross section. These sections may be of any suitable form. A hoop section 4' having a different cross sectional form is shown in Fig. 7.

What I claim is:

1. An airship structure comprising an elongated yieldable and resilient frame; and a longitudinally yieldable and resilient metal envelope enclosing said frame.

2. An airship structure comprising an elongated frame; a longitudinally resilient metal envelope structure enclosing said frame and connected to it to exert a yieldable longitudinal tension; and adjustable means to vary said tension.

3. An airship structure comprising an elongated frame; and a longitudinally resilient metal envelope enclosing said frame and anchored to it at spaced points along its length, the said envelope being adapted to exert a yieldable tension between said points of connection with the frame.

4. An airship structure comprising an elongated frame; a longitudinally resilient metal envelope enclosing said frame and anchored to it at spaced points along its length, the said envelope being adapted to exert a yieldable tension between said points of connection with the frame; and adjustable means to vary said tension.

5. In an airship having an elongated yieldable and resilient frame structure, an envelope structure to enclose said frame structure comprising a series of annular metal sections adapted to extend transversely around the frame structure and connected together end to end longitudinally of it; and means to render the envelope structure longitudinally yieldable and resilient.

6. In an airship having an elongated yieldable and resilient frame structure, an envelope structure adapted to enclose said frame structure comprising a series of annular metal sections adapted to extend transversely around the frame structure and connected together end to end longitudinally of it, certain of said sections being formed to render the envelope structure longitudinally yieldable and resilient.

7. An airship structure comprising an elongated yieldable and resilient frame structure; an envelope structure adapted to

enclose said frame structure comprising a plurality of metal sections adapted to be disposed transversely around the frame structure and connected together end to end longitudinally of it, the envelope structure being anchored to the frame structure at longitudinally spaced points; and means rendering the envelope structure longitudinally yieldable and resilient between said spaced points.

8. An airship structure comprising an elongated yieldable and resilient frame; and a metal envelope structure enclosing said frame and formed with transversely extending corrugations to render it longitudinally yieldable and resilient.

9. An airship structure comprising an elongated yieldable and resilient frame; and an envelope structure enclosing said frame and comprising a series of annular metal sections extending transversely around said frame and connected together end to end longitudinally of it, certain of said annular sections being formed with peripherally extending corrugations to render the envelope structure longitudinally yieldable and resilient.

10. An airship structure comprising an elongated yieldable and resilient frame; and a metal envelope enclosing said frame and anchored to it at a series of longitudinally spaced points, said envelope being formed with transversely extending corrugations located between said spaced points to render the envelope longitudinally yieldable and resilient.

11. In an airship having an elongated frame structure, an envelope structure adapted to enclose said frame structure and comprising a series of annular metal sections adapted to extend transversely around the frame structure and connected together end to end longitudinally of it; and joint connections between certain of said sections adapted to allow them a relative longitudinal movement.

12. In an airship having an elongated frame structure, an envelope structure adapted to enclose said frame structure and comprising a plurality of metal sections adapted to extend transversely around the frame structure and connected together end to end longitudinally of it; joint connections between certain of said sections adapted to allow them a relative longitudinal movement; means to render the envelope longitudinally resilient, the envelope being adapted to be attached to the frame to exert a longitudinal tension; and means to adjust said joint connections to vary said envelope tension.

13. An airship structure comprising a frame; an envelope enclosing said frame and attached to it to exert a tension in one direction; and adjustable means to vary said tension.

14. An airship structure comprising a frame; an envelope enclosing said frame and anchored to it at a series of points spaced apart in one direction, the envelope being under tension between said anchored points; and adjustable means to vary the envelope tension between said points.

15. An airship structure comprising a resilient frame; a longitudinally resilient envelope enclosing said frame and attached to it to exert a tension in one direction; and adjustable means to vary said envelope tension.

16. In an airship, the combination of an elongated yieldable resilient frame structure; and an envelope structure enclosing the frame structure and comprising a series of connected longitudinally extensible metal sections formed to extend transversely around the frame structure and arranged longitudinally therealong.

17. In an airship having an elongated frame structure, an envelope structure adapted to enclose said frame structure and comprising a series of annular metal sections formed to extend transversely around the frame structure and connected together end to end longitudinally of it; joint connections between certain of said sections adapted to allow them a relative longitudinal movement; and means to render the envelope structure longitudinally yieldable and resilient.

18. In an airship having an elongated frame structure, an envelope structure adapted to enclose said frame structure and comprising a series of metal sections formed to extend transversely around the frame structure and connected together end to end longitudinally of it; joint connections between certain of said sections adapted to allow them a relative longitudinal movement; and means to render certain of the said envelope sections yieldable and resilient longitudinally of the envelope.

19. In an airship, an elongated frame structure; an envelope structure to enclose said frame comprising a longitudinal series of metal sections each formed to extend transversely around the frame structure and connected together end to end longitudinally of it; means to anchor the envelope to the frame at a series of longitudinally spaced points, certain of the envelope sections being formed between said spaced points with transversely extending corrugations to render them longitudinally yieldable and resilient; joint structures connecting together certain of said sections at points between the said anchored points and adapted to allow the joined sections a relative longitudinal movement; and means to adjust the longitudinal tension of the envelope between the said spaced points.

20. In an airship, an elongated frame structure comprising a longitudinal series of

spaced transversely disposed hoop members; resilient frame means to yieldably hold said hoop members in their proper relative positions in the series; an envelope structure to 5 enclose said frame comprising a longitudinal series of metal sections each formed to extend transversely around the frame structure and connected together end to end longitudinally of it; metal joints connecting together 10 certain of said sections at points between the hoop members and adapted to allow the joined sections a relative longitudinal movement; means to anchor the envelope to each hoop member whereby the envelope will be anchored to the frame at a series of longitudinally spaced points, certain of the envelope sections being formed between said spaced points with transversely extending corrugations to render them longitudinally yieldable and resilient; and means to adjust the longitudinal tension of the envelope between said spaced points. 15 20

In testimony whereof I hereunto affix my signature.

FERNAND E. D'HUMY.
